AUTOMATIC PUMP ASSEMBLY PRIMER

Arnold S. Soberg, Elmhurst, Ill., assignor to
Sochris Development Company, Chicago, Ill., a
corporation of Illinois

Application November 5, 1948, Serial No. 58,567

7 Claims. (Cl. 103—203)

1

This invention relates to new and useful improvements in automatic pump assembly primer adapted for use with a pump of the type utilizing a liquid column for actuating the pumping action of a piston assembly suspended in the source of water.

The primary object of this invention is to provide a device whereby a part of the pumped liquid is directed back to the liquid column of the pump assembly so that at all times the column of liquid extends to the pulsator or piston means which exerts a pressure on said column for operating the pump.

Another object of this invention is to provide an automatic primer that permits the flow of liquid from the pump therethrough to the reservoir but directs some of the pumped liquid back to the pump assembly whenever pumping operation ceases.

A further object of this invention is to provide such a device having a movable valve member adapted to receive the liquid from the pump, be moved by the liquid pressure to direct it to the liquid reservoir and when in such operating position to substantially prevent such pumped liquid from returning to the pump but which, when the pump ceases operation, will return to normal position and uncover a return port leading to the pump assembly through which liquid from the reservoir may flow to maintain adequate liquid in the pump assembly.

Still a further object of this invention is to provide an automatic pump primer which will, even during pumping operations, permit some of the pumped liquid to go back to the pump assembly should it be needed.

Other objects and advantages will become apparent from the following specification.

In the drawings:

Fig. 1 is a schematic view showing a pump assembly utilizing the automatic pump primer embodying this invention.

Fig. 2 is an enlarged sectional view of the automatic primer itself.

Fig. 3 is a sectional view similar to Fig. 2 but in operating position.

Fig. 4 is a cross sectional view of the primer device taken along line 4—4 of Fig. 2.

In detail, 1 indicates a well casing within which is suspended a pumping mechanism 2. A pulsator 3 is a device for varying the pressure on the liquid column filling the well casing 1, well known in the art, and is connected with casing 1 by means of a conduit 4. The automatic primer or feed back embodying this invention is indi-

cated by 5 and a conduit 6 leads from casing 1 to primer 5. A conduit 7 connects primer 5 with pulsator 3 and conduit 8 connects the primer 5 with a liquid reservoir 9.

Referring now to Fig. 2, which illustrates the details of the automatic pump primer, the primer comprises a hollow casing 10 provided with a cover 11, an inlet chamber 12, an intermediate outlet 13 and an upper outlet 14. A central vertical tube 15 provides a channel leading from inlet chamber 12 to upper outlet 14. Just below the upper outlet 14 tube 15 is provided with a port 16, connecting with a passageway 17 leading to outlet 13 around the tube 15.

Within tube 15 is positioned a vertically movable capped tubular valve member 18 having outlet ports 19 in its side wall adjacent its top. A small port 20 is in the wall of member 18 near its lower end and positioned so as to align with port 16 when member 18 is in its upper operative position. A spring 21 extends between the cover 11 and the top of member 18 to permit its upward sliding movement during pumping operations but to return it to normal position when the pump is not in operation.

Inlet chamber 12 is normally closed by a spring valve assembly comprising an apertured cap 22, closure member 23, valve stem 24 and spring 25. It is obvious that pressure through the apertures in cap 22 against member 23 will open the valve against the pressure of spring 25 to admit liquid to chamber 12.

In operation, liquid from pump mechanism 2 is pumped through conduit 6 to the primer 5. The pressure of the pumped liquid opens the valve member 23 to inlet chamber 12 and the liquid flows upwardly into tubular valve member 18 and causes it to move upwardly against the action of spring 21 until it reaches the position shown in Fig. 3. Ports 19 align with outlet 14 and the liquid flows therefrom through conduit 8 to reservoir 9. During this operation small port 20 which is aligned with port 16 in tube 15 provides escape for any air or other gas which may have entered through port 13. In the absence of port 20 such air or other gas would form a pocket which would reduce the efficiency of the pump.

When the pumping operation ceases valve member 23 closes and tubular member 18 returns to the position shown in Fig. 2. In this position the port 16 is connected with outlet 14 which leads to the reservoir 9. Thus the liquid from reservoir 9 is allowed to flow back into outlet 14 through port 16 and passageway 17 to outlet 13 from

which it returns to the water column on which the pulsator operates, if it is needed. Obviously if the water column is adequate and there is no air space between it and the pulsator only enough liquid will flow from the reservoir to fill conduit 7 and conduit 8 through the primer. In this manner the water column is always maintained against the operative mechanism of the pulsator which is essential to the proper and efficient operation of the pump assembly.

I claim:

1. An automatic pump assembly primer for combination with a pump and a liquid reservoir comprising a hollow casing provided with an inlet port and two outlet ports, a channel connecting the inlet port with one of the outlet ports, a movable valve member in said channel normally closing it, a separate passageway connecting the two outlet ports through said channel, said valve member movable under pressure of liquid entering the inlet port to close said passageway and open said channel to permit liquid to flow therethrough, said valve member returnable to its original position to open the passageway to permit liquid to flow from one outlet to and from the other outlet when liquid ceases to be forced into the inlet port.

2. An automatic pump assembly primer for combination with a pump and a liquid reservoir comprising a hollow casing, an inlet pump port, an outlet port, a reservoir port, a channel leading from the inlet pump port to the reservoir port, a separate passageway leading from the outlet port to the channel, a slideable valve member in said channel normally closing the channel below the passageway but movable to open the channel and close the passageway to alternately permit flow from the inlet port through the channel to the reservoir port and from the reservoir port through the passageway to the outlet port.

3. An automatic pump assembly primer comprising a hollow casing, an inlet port, an outlet reservoir port and an outlet primer port, an irreversible inlet valve in said inlet port, a channel leading from said inlet port to said reservoir port, a passageway leading from said outlet primer port and joining the upper part of said channel below the reservoir port, a movable valve in said channel normally positioned below the point of juncture of the passageway and the channel and closing the channel, said valve adapted to be moved upwardly to open the channel to connect the inlet port with the reservoir port and simultaneously close the passageway and returnable to open the passageway to connect the reservoir port with the outlet primer port and close the channel.

4. An automatic pump assembly primer comprising a hollow casing, an inlet port, an outlet reservoir port and an outlet primer port, a tubular channel connecting the inlet port with the reservoir port, a passageway leading from the outlet primer port to the upper part of the channel, a slideable tubular valve member normally closing the channel below its upper port, an outlet in the upper side part of said valve member, said member movable upwardly in said channel under pressure of water entering said inlet port to connect said channel with the reservoir port through its outlet and to simultaneously close said passageway and means for returning the member to a point below the upper part of the channel to open the passageway from the reservoir port to the outlet primer port.

5. An automatic pump assembly primer comprising a hollow casing, a lower inlet port ad-

4
jacent the bottom of the casing, an intermediate primer port, an upper reservoir port, a channel leading from the inlet port to the reservoir port, a separate passageway leading from the primer port and connecting with the upper part of the channel below the reservoir port, a hollow, capped, valve member slidably positioned in said channel below its upper part to close said channel, means resiliently holding it in said position, an outlet port in the side of said valve member adjacent its capped top and normally closed by the wall of said channel, said member movable upwardly to align its outlet with the reservoir port to open the channel from the inlet port and at the same time close said passageway, whereby liquid may flow from the inlet port through the channel and out of the reservoir port when in its upper position and whereby in its normal position liquid may flow from the reservoir port through the passageway and out of the primer port.

6. An automatic pump assembly primer comprising a hollow casing, a lower inlet port adjacent the bottom of the casing, an intermediate primer port, an upper reservoir port, a channel leading from the inlet port to the reservoir port, a separate passageway leading from the primer port and connecting with the upper part of the channel below the reservoir port, a hollow, capped, valve member slidably positioned in said channel below its upper part to close said channel, means resiliently holding it in said position, an outlet port in the side of said valve member adjacent its capped top and normally closed by the wall of said channel, an air vent in the side of said valve member below the outlet port, said member movable upwardly under pressure of liquid entering the lower inlet port to align its outlet port with the reservoir port and the air vent with the passageway but otherwise closing said passageway, whereby liquid entering the inlet port under pressure will flow through the channel and out of the reservoir port and air will be drawn through the vent from the primer port, and when the inflow of liquid ceases the valve will return to normal position and liquid will flow from the reservoir port through the passageway and out of the primer port.

7. In combination with a pulsator, a pump and a reservoir, an automatic primer comprising a hollow casing having an inlet port, a primer port and a reservoir port, a conduit connecting the pump with the inlet port, a conduit connecting the pulsator with the primer port, a conduit connecting the reservoir port with the reservoir, a channel in the primer connecting the inlet port with the reservoir port, a separate passageway connecting the primer port with the reservoir port, a slideable valve member in said channel normally closing it but movable to open it and close the passageway whereby in closed position liquid from the reservoir will flow therefrom to the pulsator if needed and in open position liquid will be directed from the pump to the reservoir.
